US00D400967S

United States Patent [19]

Schreiner et al.

[11] Patent Number: Des. 400,967

[45] Date of Patent: **Nov. 10, 1998

[54] **COMBINATION VALVE AND VALVE ACTUATOR**

[75] Inventors: **Michael R. Schreiner**, Port Washington; **John H. Schlais**, New Berlin, both of Wis.

[73] Assignee: **Erie Manufacturing Company**, Milwaukee, Wis.

[**] Term: **14 Years**

[21] Appl. No.: **79,079**

[22] Filed: **Nov. 7, 1997**

[51] LOC (6) Cl. **23-01**

[52] U.S. Cl. **D23/233**

[58] Field of Search D23/233-237, D23/244-249; 251/58, 30.01, 63.5; 285/328; 137/556

CLAIM

The ornamental design of a combination valve and valve actuator, as shown and described.

DESCRIPTION

FIG. 1 is an isometric view of a combination valve and valve actuator incorporating our new design, with the broken line showing for illustrative purposes only and forming no part of the claimed design;

FIG. 2 is a left side elevation view thereof;

FIG. 3 is a right side elevation view thereof;

FIG. 4 is an end elevational view thereof;

FIG. 5 is an opposite end elevational view thereof;

FIG. 6 is a top plan view thereof;

FIG. 7 is a bottom plan view thereof;

FIG. 8 is an isometric view of a valve body for use in combination with an actuator as in FIGS. 1-7, incorporating our new design;

FIG. 9 is an end elevational view thereof;

FIG. 10 is an opposite end elevational view thereof;

FIGS. 11 and 12 are side elevation views thereof;

FIG. 13 is a top plan view thereof; and,

FIG. 14 is a bottom plan view thereof.
